ALFONS H. NEULAND, OF SAN FRANCISCO, CALIFORNIA, ASSIGNOR TO NEULAND MAGNETO COMPANY, OF SAN FRANCISCO, CALIFORNIA, A CORPORATION OF CALIFORNIA.

COMBINED LIGHTING AND IGNITION SYSTEM.

1,148,709.

Specification of Letters Patent. Patented Aug. 3, 1915.

Original application filed September 3, 1912, Serial No. 718,237. Divided and this application filed July 8, 1913. Serial No. 777,835.

To all whom it may concern:

Be it known that I, ALFONS H. NEULAND, a subject of the Czar of Russia, and a resident of the city and county of San Francisco and State of California, have invented certain new and useful Improvements in Combined Lighting and Ignition Systems, of which the following is a specification.

The invention relates to magnetos which are used in connection with internal combustion engines to generate the electric current for producing the firing spark.

The object of the invention is to produce a magneto of substantially the same size as now in general use, which is capable of producing the desired spark and current for illumination purposes.

A further object of the invention is to provide means in combination with the magneto for producing a proper distribution of the current to the spark plugs and illuminating circuit.

This application is a division of my prior application, Serial Number 718,237 filed Sept. 3, 1912.

It is the present tendency in automobile practice to illuminate the lights on the car with electricity, and heretofore, it has been necessary to install a separate generator or battery for this purpose. It is also desirable to produce a spark in the engine cylinders while the engine is at rest, for the purpose of starting the engine, without cranking, and this has heretofore necessitated the use of a separate battery. These results are accomplished by the magneto of my invention, without making the magneto of greater size than is now the general practice.

The invention possesses other advantageous features, which, with the foregoing, will be set forth at length in the following description where I shall outline in full that form of the invention which I have selected for illustration in the drawings accompanying and forming part of the present invention. The novelty of the invention will be included in the claims succeeding said description. From this it will be apparent that I do not limit myself to the showing made by said drawings and description, as

I may adopt many variations within the scope of my invention as set forth in said claims.

Referring to said drawings: Figure 1 is a vertical longitudinal section taken through the magneto. Fig. 2 is a transverse section taken on the line *a—a* Fig. 1. Fig. 3 is a partial sectional view taken on the line *b—b* Fig. 1. Fig. 4 is an end view of the distributor. Fig. 5 is a side view of the distributor. Fig. 6 is a diagrammatic representation of one form of the electric circuits connecting the magneto with the sparking and lighting circuits.

The magneto consists of a suitable frame 2 in which is secured the permanent magnet 3. This magnet is formed of a plurality of laminated plates 4 securely held together and to the frame by the bolts 5. The plates 4 are preferably circular in form, as shown in Fig. 2 and are formed with arms or pole-pieces 6 and 7 of opposite polarity. The pole-pieces are divided into two sections 6^a—6^b and 7^a—7^b by the groove or channel 8, but the two sections 6^a—6^b are of one polarity and the sections 7^a—7^b are of the opposite polarity. The inner faces of the pole-pieces are provided with teeth 16^a—16^b—17^a—17^b arranged parallel to each other and extending in the direction of the length of the magnet. The teeth on each section are equally spaced apart from each other, and the two adjacent teeth on the sections of one pole-piece are spaced apart a distance equal to one-half or an odd multiple of one-half the spacing of the teeth on each section. That is, the adjacent teeth 16^a—16^b or 17^a—17^b have a pitch of one-half or an odd multiple of one-half the pitch of the teeth 16^a or 16^b or 17^a or 17^b.

Mounted in the frame and rotatable between the pole-pieces is a core 12 which is formed of laminations securely held together. The core is provided with teeth 13 which are spaced apart the same as the teeth on the sections of the pole-pieces. It is evident that as the core revolves, the teeth thereon coincide alternately with the teeth on sections 16^a—17^a and 16^b—17^b, producing a flux first from 16^a to 17^a, and then from 16^b to 17^b. Since the core serves to shift the

passage of the magnetic flux alternately through the sections 6^a—7^a and 6^b—7^b, I shall hereinafter refer to it as a flux valve. It is evident that a rotation of the flux valve 5 through a distance equal to one-half the spacing of the teeth will cause a shifting of the lines of force.

Arranged in the channels or grooves 8 is a coil or winding 14 in which the current is induced, due to the shifting of the lines of force passing therethrough. Since each reversal of the magnetism through the coil induces an electromotive impulse in the coil, it is evident that a large number of impulses 15 are produced for each revolution of the flux valve, the number of impulses being twice the number of teeth on the valve. On account of the large number of impulses generated per revolution, this form of magneto 20 is particularly applicable for use in connection with an ignition and lighting system.

The magneto illustrated in the drawings is adapted to be used in connection with a 25 four cylinder, four cycle engine, but it is evident that the distributor can be altered to conform to any design of engine. Since the duration of the spark used for igniting the explosive charge is of short duration, it 30 is necessary to employ only a small number of the impulses generated in the coil for sparking purposes, allowing the greater number of such impulses to be used for other purposes, such as the illumination of 35 head-lights or the operation of electric horns and whistles.

The core or flux valve is mounted on the shaft 21 which is driven by the engine shaft 22 through the gears 23—24 which are of 40 such size that the shaft 21 makes two revolutions for each revolution of the engine shaft. The gear 24 is fixed to the sleeve 25 which is mounted for independent rotation on the shaft 21. The sleeve 25 is provided 45 on its outer end with a single tooth ratchet 26 which engages a similar ratchet on the sleeve 27, which is movable longitudinally of the shaft but is splined thereto, so that it rotates with the shaft. The sleeve 27 is 50 held against the sleeve 25 by the spring 29 surrounding the shaft. As the engine shaft revolves, the flux valve is also revolved, through the agency of the clutch, but when the engine shaft is stationary, the flux valve 55 shaft may be rotated in the proper direction by the crank or handle 30, thereby allowing a current to be produced when the engine is at rest. This rotation does not disturb the relation between the position of 60 the distributor and the position of the pistons in the engine, so that when the engine starts the timing of the spark is correct.

Arranged between the handle 30 and the valve shaft is a clutch which becomes disengaged when the engine starts, thereby allow-

ing the handle to remain at rest. The clutch consists of the toothed member 51 formed on the sleeve 52 loosely mounted on the valve shaft and to which sleeve the handle is attached. Arranged on the valve shaft 70 is a similar toothed member 53. Bearing against the sleeve 52 is a spring 54 which operates to normally hold the toothed members apart. When it is desired to produce a spark with the engine at rest, the sleeve is 75 pushed in, compressing the spring and bringing the two parts of the clutch into mesh and the handle is rotated. The clutch on the opposite end of the shaft allows the shaft to be rotated by disengaging it from 80 the engine shaft.

Loosely mounted on the sleeve 25 is the fiber drum 31 of the distributor. This drum is rotated at the proper speed by the connected gears 32—33 mounted on the stub 85 shaft 34. Gear 32 meshes with a gear 35 formed on the end of the sleeve 25, and gear 33 meshes with a gear 36 on the drum. Embedded in the circumferential face of the drum is a metal ring 37 having an offset 90 tongue or section 38, which comes into contact alternately with the brushes 41—42—43—44, which are connected to the respective spark plugs of the four cylinder engine. Bearing against the continuous 95 ring 37 is a brush 45 which is connected to one end of the secondary or high tension winding 76 of the transformer or coil in the sparking circuit; the other end of the transformer winding being grounded on 100 the engine.

In order that the current may be directed to the sparking circuit at the proper intervals and to the lighting circuit at other times, a contactor or switch operated by the 105 rotating shaft is necessary. Arranged on the valve shaft is a disk 46 having a depression 47 formed in the circumferential face thereof. Mounted on the casing or cap 48 attached to the frame of the magneto is a 110 spring held contactor arm 49 bearing a roller 55 engaging the face of the disk. It is evident that as the disk revolves, the roller moves into and out of the depression 47, causing a movement of the free end of 115 the arm 49. Secured to the free end of the arm is a sleeve 56 in which are arranged at opposite ends, the contact points 57—58. Mounted on the casing 48 and insulated 120 therefrom and from each other are terminals 61—62 of the sparking and lighting circuits respectively. These terminals are arranged adjacent the contact points 57—58 so that when the roller is riding over the face of the disk, the point 58 is in contact with terminal 62 closing the lighting circuit and opening the spark circuit, and when the roller enters the depression in the disk, the point 57 is in contact with terminal 61, 125 closing the sparking circuit and opening the 130

lighting circuit. The interruption of the lighting circuit is so short, that the effect thereof is not visible at the lamps 63.

In order that no sparking may occur at these contacts as the circuits are opened and closed, I arrange the contact points so that the circuit to be made is established before the existing circuit is broken. This is accomplished by making the contact points 57—58 slidable within the sleeve 56 and holding them pressed apart by the spring 64. That point which is in circuit is pressed into the sleeve by the contacting terminal, to such an extent, that as the sleeve moves 15 away from said terminal, the point does not reach the end of the sleeve and be separated from the terminal until the other terminal and contact point are in contact.

Attached to the casing 48 at a suitable place is a rocker arm 65 to which is attached a lever or arm for rotating the casing when it is desired to advance or retard the spark. Switches 66 and 67 are provided in the spark circuit and lighting circuit respectively, so 25 that either one may be disconnected when desired.

One end of the coil 14 is connected to the contactor arm 49 and the other end is connected with the lighting circuit and with the 30 low tension side of the sparking circuit. In Fig. 6 I have illustrated one of the possible arrangements of conductors, but this may be varied as desired, and I do not desire to limit myself to any particular arrangement 35 of circuits.

I claim:

1. The combination with an internal combustion engine, of a magneto, an ignition circuit inductively connected to the generating coil of said magneto, a lighting circuit directly connected to said generating coil, and means driven by the engine for opening and closing said lighting circuit.

2. In a power propelled vehicle, an internal combustion engine, a magneto driven thereby, an ignition circuit for said engine inductively connected to the generating coil of said magneto, electric lights on said vehicle, a circuit including said lights directly connected to said generating coil, and means for alternately diverting the power generated in said coil to said ignition and lighting circuits.

3. The combination with an internal combustion engine and electric lights, of a magneto adapted to be driven by said engine, an ignition circuit for said engine inductively connected to the generating coil of said magneto, a circuit including said lights directly connected to said generating coil, and means operative by the rotation of the rotating part of the magneto for alternately diverting the power generated to said ignition and lighting circuits.

4. In a power propelled vehicle, an inter-

nal combustion engine, a magneto driven thereby having a generating coil, a lighting circuit directly connected to said coil, a primary transformer winding directly connected to said coil, a secondary transformer 70 winding, an ignition circuit directly connected to said secondary winding, and means between the generating coil and the lighting and primary winding circuits for alternately diverting the power generated 75 to said circuits.

5. In a power propelled vehicle, an internal combustion engine, a magneto connected thereto adapted to generate a large number of impulses per revolution, a two contact 80 low tension diverter included in circuit with the generating coil of the magneto, a lighting circuit connected at one end to the generating coil, and at the other end to one outer contact of the diverter, a step up 85 transformer having its primary in circuit between one end of the generating coil and the other outer contact of the diverter, and an ignition circuit including the secondary of the transformer, said diverter serving to 90 time the ignition spark and to convey the greater part of the generated impulses to the lighting circuit.

6. In a power propelled vehicle, an internal combustion engine, a magneto, having a 95 generating coil, arranged to be driven by said engine, a movable contact connected to one end of said coil, contacts arranged at opposite sides of said movable contact arranged to be alternately engaged thereby, a 100 lighting circuit bridged across one of said contacts, and the other end of the generating coil, a circuit including the primary winding of a transformer bridged across the other contact and the other end of the generating 105 coil, and an ignition circuit including the secondary winding of said transformer.

7. In a power propelled vehicle, the combination with an internal combustion engine, of a generator constructed to produce 110 a large number of impulses per revolution, a transformer having its primary winding connected to said generator and having its secondary winding in the ignition circuit, the ignition circuit, a lighting circuit arranged to be directly connected to said generator, and means for alternately connecting the lighting circuit and the transformer primary winding with said generator.

8. The combination with a magneto 120 adapted to produce a large number of impulses per revolution, of ignition and lighting circuits, and means for distributing alternately a relatively large number of consecutive impulses to the lighting circuit and a relatively smaller number of impulses to the ignition circuit.

9. The combination of a magneto adapted to produce a large number of impulses per revolution, of an ignition circuit, a lighting 130

circuit directly connected to the generating coil of the magneto, and means for distributing a series of consecutive impulses of each revolution to the lighting circuit and the remainder of said impulses to the ignition circuit.

10. The combination with an internal combustion engine, of a magneto, adapted to produce a large number of impulses per revolution, an ignition circuit inductively connected to the generating coil of said magneto, a lighting circuit directly connect-

ed to said generating coil, and means for alternately directing a minor portion of said impulses to the ignition circuit and the major portion of said impulses to the lighting circuit. 15

In testimony whereof, I have hereunto set my hand at San Francisco, California, this 2nd day of July 1913.

ALFONS H. NEULAND.

In presence of—

P. S. PIDWELL,
H. G. PROST.
